UNITED STATES PATENT OFFICE.

ANTHONY E. DAVIS, OF PHILADELPHIA, PENNSYLVANIA.

SIGN EXHIBITOR.

Application filed June 25, 1924. Serial No. 722,189

My present invention comprehends a novel construction and arrangement of a sign exhibitor which can be economically manufactured, and wherein, when desired, 5 the sign can be readily removed and replaced by another sign.

It further comprehends a novel sign exhibitor formed of an outer frame to which are secured slot forming guides to receive 10 the sign, and wherein one of said guides is readily removable in order that one sign may be removed and another sign may be inserted and fixed in place.

Other novel features of construction and 15 advantage will hereinafter more clearly appear in the detailed description and the appended claims.

For the purpose of illustrating the invention, I have shown in the accompanying 20 drawing a typical embodiment of it, which, in practice, will give reliable and satisfactory results. It is, however, to be understood that this embodiment is typical only and that the various instrumentalities 25 of which my invention consists can be variously arranged and organized, and that the invention is not limited to the precise arrangement and organization of these instrumentalities as herein set forth.

30 Figure 1 is a front elevation of a sign exhibitor embodying my invention.

Figure 2 is an end elevation thereof.

Figure 3 is a perspective view of a removable guide, in detached position.

35 Figure 4 is a section on line 4—4 of Figure 1.

Figure 5 is a front elevation of another embodiment of my invention.

Similar numerals of reference indicate 40 corresponding parts.

Referring to the drawings:

1 designates a sign exhibitor, embodying 45 my invention. The sign exhibitor is provided with a frame 2 preferably formed from sheet material which is bent into any desired formation, and the juxtaposed free ends of such frame are preferably welded together as indicated at 3.

4 and 5 designate permanent guides, preferably in the form of angles, the faces of the angles being disposed substantially at right angles to each other. These guides are secured to the inner face of the frame 2 in spaced relationship to each other by 55 means of fastening devices 6 such, as 101

example, rivets. The guide 5 extends entirely around the frame 2 but the side arms or members of the guide 4 terminate intermediate opposite sides of the frame as indicated at 7, in order that the sign 8 may 60 be inserted in the slot formed between the guides 4 and 5. 9 designates a removable guide member in the form of an angle, the ends of which are deflected to form side members 10, which, when inserted within the 65 frame 2 as shown in Figure 1, form a continuation of the side members of the guide 4. This removable guide 9 is secured in fixed position by means of fastening devices 11, such as bolts and nuts or equivalent fastening devices. The apertures in the frame 70 to receive the fastening devices 11 are preferably countersunk in order to form a flush joint with the outer face of the frame.

The frame is supported by means of the 75 base 12 which consists of a bar of sheet material which is bent to form the table 13 from which the bar diverges downwardly as at 15 and terminates in the foot flanges 15. The bar is braced by means of a brace bar 80 or member 16 having flanges which are welded or otherwise connected to the diverging members 14. The base members 12 are connected to the frame by means of fastening devices 17, such as, for example, the 85 bolts and nuts shown.

In the embodiment of my invention, shown in Figure 5, the construction is the same, except that the free ends of the frame, instead of being welded together, terminate in proximity to each other preferably at the bottom of the frame and are secured thereto by certain of the fastening devices, 6.

When it is desired to remove the sign, 95 all that it is necessary to do is remove the fastening devices 11 and remove the guide 9, whereupon the sign can be readily removed from the slot formed between the guides 4 and 5, as is apparent. When a new 100 sign is inserted into such slots, its removal is prevented by securing the removable guide 9 in place by means of the fastening devices 11, as is shown in Figure 1.

The base, the frame and the guide are 105 preferably formed from sheet metal so that the sign exhibitor will be rigid and durable, and so that it can be economically manufactured.

If desired, the base of the frame may be 110

provided with the apertures 18 which form drainage ports so that water flowing down the sign can pass through such ports.

My invention is especially designed to be shipped in a knock-down condition. The base consisting of the supporting members 12 can be removed and placed within the frame so that a flat container can be employed. In devices of this character as 10 heretofore manufactured the base or supporting frame work has been permanently connected with the frame, and as the base was wider than the thickness of the frame, the sign exhibitors were difficult to pack and 15 the cost of packing and shipping were very great. The sign exhibitor herein disclosed can be readily taken apart and assembled by unskilled labor and when shipped in a knock-down condition form a package of 20 minimum size, and of uniform dimensions, with consequent economy in the cost of packing and shipping.

It will now be apparent that I have devised a new and useful sign exhibitor which 25 embodies the features of advantage enumerated as desirable in the statement of the invention and the above description, and while I have, in the present instance, shown and described a preferred embodiment 30 thereof which will give in practice satisfactory and reliable results, it is to be understood that this embodiment is susceptible of modification in various particulars without departing from the spirit or scope of 35 the invention or sacrificing any of its advantages.

Having thus described my invention, what I claim as new and desire to secure by Letters Patent, is:

1. In a sign exhibitor, a frame comprising an outer member, spaced slot forming guides secured to said member, one of said guides terminating intermediate opposite sides of said frame, and a removable sign securing member forming a continuation of 45 one of said guides and spaced from the other of said guides.

2. In a sign exhibitor, a frame comprising an outer member, an angle secured to the inner face of said member, a second angle 50 secured to said member in spaced relationship to said first angle to form a sign receiving slot extending upwardly from the bottom of said frame, and a third removable angle secured to said member to form 55 a continuation of said second member and prevent the improper removal of said sign.

3. In a sign exhibitor, a frame comprising an outer member, spaced slot forming guides secured to said member, one of said 60 guides terminating intermediate opposite sides of said frame, a removable sign securing member forming a continuation of one of said guides and spaced from the other of said guides, and a base detachably connected with the bottom of said frame, 65 whereby the frame can be shipped in a knockdown condition, said base when in knockdown condition with the frame being disposed within the planes of the frame to 70 form a package of minimum size.

ANTHONY E. DAVIS.
